United States Patent Office

Des. 198,444
Patented June 16, 1964

198,444

SOLAR HOUSE

Harry E. Thomason, District Heights, Md.
(7354 Walker Mill Road SE, Washington 27, D.C.)

Filed June 18, 1963, Ser. No. 75,411

Term of patent 14 years

(Cl. D13—1)

Fig. 2.

Fig. 1.

FIGURE 1 is a front view of the house from the east,
FIGURE 2 is a rear view, from the west,
FIGURE 3 is a view from the south, and
FIGURE 4 is a view from the north.

For convenience of illustration, only parts of the brick surfaces have been shown in the several views of the drawings. It is to be understood that these surfaces continue throughout the areas indicated.

I claim:
The ornamental design for a solar house, substantially as shown and described.
